UNITED STATES PATENT OFFICE.

ROBERT A. HAMMOND, OF SANDWICH, SYDNEY E. TAFT, OF SOUTH FRAMINGHAM, AND CHARLES S. GOODING, OF BROOKLINE, MASSACHUSETTS; SAID TAFT AND GOODING ASSIGNEES TO SAID HAMMOND.

LOOM.

1,192,302.

Specification of Letters Patent. Patented July 25, 1916.

Application filed October 14, 1907, Serial No. 397,315. Renewed September 9, 1914. Serial No. 860,965.

To all whom it may concern:

Be it known that we, ROBERT A. HAMMOND, a citizen of the United States, residing at Sandwich, county of Barnstable, 5 SYDNEY E. TAFT, a citizen of the United States, residing at South Framingham, county of Middlesex, and CHARLES S. GOODING, a citizen of the United States, residing at Brookline, in the county of Norfolk, all 10 in the State of Massachusetts, have invented new and useful Improvements in Looms, of which the following is a specification.

This invention relates to looms particularly adapted to weaving heavy material 15 and is constructed for the specific purpose of weaving flat wire belts or ropes of the character set forth in U. S. Letters Patent to Jacob Kast, No. 841,154, patented January 15, 1907, in which two filling strands are 20 interwoven with the longitudinal strands. The device of this invention is, however, adapted to weave a fabric or belt with a single filling strand as well as with two filling strands.

25 The object of the invention is to provide a loom of the character set forth in which the strands for the filling are wound upon reels and the reels are moved transversely of the warp between the shed simultaneously in 30 opposite directions, then resting while the shed changes, the fabric feeds, the take-up operates, and the filling is beaten up.

The invention consists in the combination and arrangement of parts set forth in the 35 following specification and particularly pointed out in the claims thereof.

Referring to the drawings: Figure 1 is a front elevation of our improved loom. Fig. 2 is a right hand side elevation of the same. 40 Fig. 3 is a vertical sectional elevation taken on line 3—3 of Fig. 2, illustrating the reversible and auxiliary clutch mechanisms and the shafting and gearing connected therewith, the same being broken away to 45 save space in the drawings. Fig. 4 is a front elevation, in detail, of the feed mechanism, a portion of the frame being shown in connection therewith and broken away to save space. Fig. 5 is a detail front elevation 50 of the beat-up mechanism, together with the rolls for guiding and forming the fabric after it is woven, a portion of the frame being shown in connection therewith, broken away and shown in section on line 55 5—5 of Fig. 2, looking toward the right in

said figure. Fig. 6 is a plan of the lower reel and driving mechanism therefor, the frame and vertical driving shaft being shown in section and the carrier slide being broken away to save space in the drawings. 60 Fig. 7 is a sectional elevation of the lower reel and its driving mechanism taken on line 7—7 of Fig. 6 looking in the direction of the arrow on said line. Fig. 8 is a sectional elevation of the lower reel and a portion of the frame, taken on line 8—8, Fig. 6 with the slide upon which said reel is journaled and the carrier slide shown in connection therewith, the same being broken away to save space. Fig. 9 is a detail sectional elevation taken on line 9—9 of Fig. 1, illustrating the mechanism for adjusting the tension on the heddle connections and a portion of the mechanism by which said heddles are reciprocated. Fig. 10 is a sectional elevation taken on line 10—10 of Fig. 3, illustrating the auxiliary clutch mechanism. Fig. 11 is a sectional elevation taken on line 11—11 of Fig. 3, illustrating the reversing clutch mechanism. Fig. 12 is a detail front elevation of the switch cam forming a portion of the auxiliary clutch mechanism. Fig. 12 is a detail front elevation of the switch cam forming a portion of the auxiliary clutch mechanism. Fig. 13 is a sectional elevation taken on line 13—13 of Fig. 1, illustrating the mechanism for changing the harness. Fig. 14 is a detail sectional elevation taken on line 14—14 of Fig. 2, illustrating the means for adjusting the rolls which bear against the edge of the fabric to form the same. Figs. 15, 16 and 17 are illustrative details of the lay and reed. Fig. 18 is an enlarged front elevation illustrating the clutch mechanisms and the instrumentalities by means of which they are operated when the lower reel and its slide are at the left of the machine. Fig. 19 is a view similar to Fig. 18 showing the position of the clutch mechanisms when the lower reel and its slide are at the right of the machine. Fig. 20 is a front elevation of the clutch mechanisms showing the same in the relative positions occupied thereby when the reversing clutch is moved to its extreme position toward the left, the auxiliary clutch being thrown out of engagement and the mechanism in position to reverse the direction of movement of the reels and their slides, so that the lower reel will 110

be just starting to move toward the left and the upper reel in the opposite direction. Fig. 21 is a detail side elevation, partly in section and broken away, of one of the heddles and its flexible connections and the guide rolls therefor. Fig. 22 is an enlarged plan view of the upper guide rolls for the heddle connections. Fig. 23 is a detail sectional elevation taken on line 23—23 of Fig. 10. Fig. 24 is a detail side elevation of a modified form of harness and its operating mechanism with the heddles attached thereto. Fig. 25 is a plan view of the upper guide pulleys of said harness. Fig. 26 is a section of the wire belt which the loom is intended to weave, and Fig. 27 is a section taken on line 27—27 of Fig. 26.

Like numerals refer to like parts throughout the several views of the drawings.

20 In general, the operation of the loom which is hereinafter specifically described and its general operation hereinafter more particularly described, is as follows: The strands of wire rope which form the warp 25 pass from reels, upon which they are wound, through a take-up device, thence to heddles forming the shed and from the shed the fabric, after it is woven and the filling beaten up therein, passes through two horizontal rolls which press against the surfaces 30 of the belt in order to straighten said belt and make it smooth and also between two edge rolls which bear against the edges of the belt in order to still further straighten 35 said belt. From these compressing rolls, the belt passes between feed-rolls to a convenient reel upon which it is wound. The filling is also wound upon a reel and consists of two filling strands, one wound upon each 40 reel, the reels being located upon opposite sides of the warp at the same time. These reels are propelled in opposite directions simultaneously by suitable mechanism from one side of the shed to the other and are carried 45 upon slides which slide in ways extending outwardly from the shed upon opposite sides thereof, said slides being so arranged and of such dimensions that they reach the ways upon one side of the shed before leaving 50 the ways upon the other and also engage the driving mechanism upon one side of the shed before leaving the driving mechanism upon the other side thereof. When the shed is open these reels are propelled, as 55 hereinbefore stated, in opposite directions simultaneously through said shed. After they have passed through the shed, the lay operates to beat up the filling thread, the heddles operate to change the shed, the feed 60 rolls operate to feed the fabric, and the take-up mechanism operates simultaneously with the heddles to preserve the proper tension upon the warp-threads forming the shed.

65 The reels and the other mechanism herein-

before referred to are automatically driven at the proper time to secure the results hereinbefore set forth and this is accomplished by means of two clutch mechanisms, one clutch mechanism being a reversing clutch 70 mechanism and connected by a suitable mechanism to the reels to impart an intermittent reciprocating motion thereto, while the other clutch mechanism is an auxiliary mechanism which operates different instrumentalities to operate the heddles, the beat-up, the feed, and the take-up.

The slides upon which the reels are journaled are driven in opposite directions and one of said slides at one end of its movement strikes a tripper lever which, through suitable mechanism, operates to throw the clutch mechanism into its central position and the reel slide then stops. During this throwing out operation, the auxiliary clutch is thrown 80 into operation, and while the slides with the reels thereon are stationary, the heddles, beat-up, feed and take-up are operated in their proper order. When they have been operated, as desired, to beat up the filling 85 thread, change the shed, feed the fabric, and operate the take-up in proper time, the auxiliary clutch is thrown out and the reversing clutch mechanism thrown in, whereupon the slides carrying the reels move in opposite 90 directions and carry the strands across for a new pick.

The specific mechanism by which the operations hereinbefore referred to in general are accomplished will now be described.

100 The main driving shaft 30 (Figs. 2, 10 and 11) is journaled in suitable bearings in the frame 31 and has fastened thereto pinion gears 32 and 33. The pinion 32 meshes into the gear 34 and the pinion 33 meshes into an intermediate gear 35 which, in turn, meshes into a gear 36. The gears 34 and 36 are both journaled to rotate upon the clutch shaft 37 (Fig. 3). The shaft 37 has fastened to the right hand end thereof (Figs. 1, 2 and 3) a bevel gear 38 which meshes into a bevel gear 39 fast to the vertical shaft 40 and also meshes into a bevel gear 41 fast to a vertical sleeve 42. The vertical shaft 40 rotates within the sleeve 42 in an opposite direction therefrom and both sleeve and shaft are supported upon suitable bearings in the frame of the machine. The sleeve 42 at its upper end is fastened to a spur gear 43 and the shaft 40 has fastened to its upper end a spur gear 44. These gears 43 and 44 operate to drive the lower and upper carrier slides for the lower and upper reels at the right hand end of the loom, respectively.

110 The left hand end of the clutch shaft 37 has fastened thereto a bevel gear 45 which meshes into a bevel gear 46 fast to the vertical shaft 47. Said shaft 37 also has fastened thereto a bevel gear 48 which meshes 115

into a bevel gear 49 fast to the vertical sleeve 50. The shaft 47 rotates within the sleeve 50 and in the opposite direction therefrom. The shaft 47 and sleeve 50 rotate in suitable bearings in the frame. At its upper end the shaft 47 has fastened thereto a spur gear 51, while the sleeve 50 has fastened to its upper end a spur gear 52, (see Figs. 1, 6 and 7). The spur gear 52 meshes into a rack 53 fast to a channel shaped carrier slide 54. Said carrier slide is adapted to be reciprocated in ways 55, 56 formed in brackets 57 and 58, respectively, fastened to the frame of the machine upon opposite sides of the shed (Fig. 1).

Within the channel carrier slide 54 is located a reel carrier slide 59 which is free to slide in the channel carrier slide 54. Said reel carrier slide has a stud 60 fast thereto upon which the lower reel 61 is journaled to rotate. Stops 62, 63 are fastened to the channel carrier slide 54 and limit the distance to which said reel carrier slide can be reciprocated within said channel carrier slide. The object of this construction of the reel slide being adapted to slide within the carrier slide is to make a differential sliding motion possible between the two, so that the reel will be moved across the shed, but it will not be necessary to move said reel any farther than to just clear the edge of the shed, as seen in Fig. 1.

The carrier slide 63 for the upper reel 64 has a rack 65 fast thereto into which the gear 51 meshes. Said carrier slide 63 has an auxiliary slide 66 adapted to slide therein which has a stud 67 fast thereto upon which is journaled the upper reel 64. The auxiliary or reel slide 66 is adapted to slide within the carrier slide 63 and is limited by stops at opposite ends of said carrier slide as to its motion relatively thereto.

When the clutch shaft 37 is rotated, it will be seen that the vertical shafts 40 and 47 rotate in the same direction and that the sleeves 42 and 50 rotate in the opposite direction from that of the shafts. The gears 43 and 52 which are attached to the sleeves 42 and 50, respectively, therefore, rotate in one direction, while the gears 44 and 51, which are fastened to the shafts 40 and 47 will rotate in the opposite direction to the rotation of said sleeves. The gears upon the shafts are adapted to mesh into the rack 65 for the carrier slide 63 of the upper reel 64, while the gears 43 and 52, fast to their respective sleeves, mesh into the rack 53 fast to the carrier slide 54 which carries the lower reel 61. Thus it will be seen that while one carrier slide, with its auxiliary slide therein and its reel rotatably supported thereon, is moving in one direction, the other auxiliary slide and reel will be moving in the opposite direction through the shed.

The upper carrier slide 63 is arranged to slide in brackets 68, 69 fast to the frame upon opposite sides of the shed. It will be seen that by stopping the shaft 37 intermittently and then reversing the same, the carrier slides with their reels will be moved first in one direction and then in the opposite direction through the shed to carry the different picks in a manner hereinafter more fully described.

Friction brakes 70, 70 (Fig. 8) are applied to the reels to prevent their rotating too freely by means of screws 71 having screw-threaded engagement with the opposite ends, respectively, of the reel slide 59.

The filling 72 is led from the reel 61 (Figs. 6 and 7) between guide rolls 73, 73 rotatably mounted upon pins 74, 74 fast to a guide frame 75 which has two arms, said arms being fastened at their free ends to opposite ends, respectively, of the slide 59, so that said filling passes from the reel 61 between the rolls 73, 73 and is thus guided between the warp threads as the reel passes through the shed. The upper reel 64 is provided with a similar device for guiding the filling strands.

The reciprocatory movement of the heddles, the movement of the lay and its reel, the movement of the take-up, and the feed of the belt as it is woven are all accomplished by certain mechanisms and instrumentalities which are actuated by an auxiliary clutch sleeve 76 (Fig. 3) which has teeth 77 adapted to engage teeth 78 upon the right hand face of the gear 34. This clutch sleeve 76 is loose on the shaft and has lateral grooves 79 into which corresponding lugs 80 project. These lugs are integral with a sleeve 81 rotatably mounted upon the shaft 37, and to this sleeve are fastened the several gears and cams which actuate the different mechanisms for operating the heddles, the heating up mechanism, the feed, and the take-up, which mechanisms we will now proceed to specifically describe.

The warp strands 82, 82 (Fig. 2) pass from reels (not shown in the drawings) beneath and partly around a roll 83 journaled to rotate upon a shaft 84 fast to brackets 85 upon the frame of the machine. Said warp strands are held upwardly against said roll 83 by a guide roll 86 journaled to rotate upon a shaft 87, the opposite ends of which are supported in arms 88 pivoted at 89 to the bracket 85. Said roll 86 is held upwardly against the under side of the warp strands by suitable adjusting screws 90. The warp strands pass upwardly around the roll 83 and over a whip roll 91 journaled to rotate upon a shaft 92 which is fastened at its opposite ends to arms 93 fast upon the shaft 84. An arm 94 is fast to the shaft 84 and has a link 95 adjustably fastened thereto, the opposite end of said link being con-

nected to a rocker arm 96 fast to a rocker shaft 97 journaled to rock in a suitable bearing in the frame of the machine and having fastened to its inner end a cam lever 98 which is provided with a cam-roll 99 adapted to bear against the periphery of a cam 100 which is fastened to the sleeve 81.

The operation of this particular mechanism is as follows: When the sleeve 81 is rotated the cam 100 being fastened thereto will rotate with it, rocking the cam lever 98, the arm 96 and, through the link 95, rocking the arm 94 and the arms 93, 93 with the whip-roll 91 thereon. This rocking movement of the whip roll 91 takes place at the time when the heddles are changing the shed and keeps the correct amount of tension upon the warp strands.

The reciprocatory motion of the heddles by means of their harness to change the shed will now be described.

Referring to Figs. 1, 2, 3, 13, 21 and 22, the heddle 101 consists of a guide-bar having a slot 102 extending longitudinally thereof and laterally therethrough, and in this slot are located two guide-rolls 103, 103 which are rotatably supported upon pins 104, 104 fast to said guide-bar. The harness by means of which the heddle is reciprocated consists of flexible connections, preferably in the present machine of wire cords or ropes, 105, 106. The connection 105 is fast to the lower end of the heddle and extends downwardly therefrom around a guide pulley 107 which is journaled upon a shaft 108 fast to the frame of the machine. The lower end of said connection 105 is fastened to an eye-bolt 109 which passes through the front bar 110 of the reciprocatory frame 111 and has screw-threaded engagement with a nut 121. Said reciprocatory frame 111 is adapted to slide in ways 112 on the side frames of the machine (Fig. 2). The connection 106 extends from the upper end of the heddle 101 over a pulley 113, thence partly around a pulley 114, over a guide pulley 115 downwardly to a guide pulley 116, thence horizontally along the reciprocatory frame 111, to the rear end of which it is fastened in the same manner as hereinbefore described in relation to the connection 105.

The guide pulleys 113, 114 and 115 are rotatably supported upon shafts 117, 118 and 119, respectively, fast to the frame of the machine, and the guide pulley 116 is journaled upon a shaft 120 fast to the frame of the machine. It will be seen that by rotating the nut 121 by means of a suitable wrench 122 (Fig. 9) the tension on the connections may be adjusted so that said flexible connections 105 and 106 may always be properly adjusted to remain taut.

The reciprocatory frame 111 has racks 123, 123 on opposite sides thereof which mesh into gears 124, 124 fast to a shaft 125

journaled to rotate upon the frame of the machine and having fastened thereto a pinion 126 which meshes into a rack-bar 127 adapted to slide in a rocker frame 128 pivoted upon the shaft 125. The rack-bar 127 is pivoted to a crank-pin 129 fast to a gear 130 fast to a stud 131 journaled to rotate in the frame of the machine. The gear 130 meshes into a gear 132 fast to the sleeve 81. It will thus be seen that when the sleeve 81 is rotated the gear 132 will be rotated, thus rotating the gear 130 and imparting a reciprocatory motion to the rack bar 127 which, as it slides in the rocker frame 128, imparts a reciprocatory motion to the pinion 126 and gear 124, whereby a reciprocatory motion is imparted to the racks 123 and the frame 111, thus alternately moving the heddles up and down through their connections 105 and 106. The crank-pin 129 is adjustable radially upon the gear 130, so that the throw of the rack-bar 127 and, therefore, of the racks 123 may be increased or diminished, as desired, to increase or diminish the throw of the heddles and the opening of the shed.

The fabric is fed, Figs. 1, 2 and 4, by means of the feed rolls 133 and 134. The feed roll 133 is fast to a shaft 135 journaled to rotate in bearings 136 formed in brackets 137 fast to the frame. A gear 138 is fastened to the shaft 135 and meshes into a gear 139 fast to the lower feed roll shaft 140. The lower feed roll shaft 140 is journaled in boxes 141 adapted to slide in slots formed in brackets 142 and adjusted in said slots by means of screws 143 to bring more or less pressure to bear upon the fabric between the rolls 133 and 134. An intermittent rotary motion is imparted to the roll 133 by a pawl 144 pivoted to a pawl-lever 145 which is mounted to rock upon the shaft 135 and to which a rocking motion is imparted by a link 146 which is connected at its lower end to a cam lever 147 pivoted to a stationary shaft 148 and having a cam roll 149 journaled thereon and arranged to bear against a cam 150 fast to the sleeve 81. It will be seen that as the sleeve 81 is rotated the cam 150 will impart a rocking movement to the lever 147 and, through the link 146, a rocking movement will be imparted to the pawl-carrying arm 145 which will move the pawl 144 to impart an intermittent rotary movement to the ratchet 151 with which said pawl is adapted to engage. A stop-pawl 144 prevents the ratchet 151 from rotating backward.

The amount of feed imparted by the rolls 133 and 134 to the fabric may be increased or diminished by means of a shield 152 which extends over the teeth of the ratchet and is fastened to a bracket 153, said bracket being adjustably fastened by means of a bolt 154 to the bracket 137 at the right of 130

Fig. 4. The bolt 154 extends through a slot 155 concentric with the axis of the shaft 135. As the fabric is fed forward, it is fed between presser rolls in order to give it an even surface and even edges. These presser rolls are illustrated in Figs. 1, 2, 5 and 14. The rolls 156 and 157 bear against the upper and lower surfaces, respectively, of the fabric, the lower roll 157 being journaled to rotate in brackets 158, 158, and the upper roll 156 is journaled to rotate in boxes which are adjusted in said brackets to bring more or less pressure to bear upon the fabric by means of adjusting screws 160, 160.

15 The edges of the fabric are formed by means of the presser rolls 161, 162 (Fig. 14) which are journaled to rotate upon studs 163, 164, respectively, said studs being formed upon boxes 165, 166 which are 20 adapted to slide in ways 167 upon the frame of the machine and are locked in position, when adjusted to the desired location, by means of locking nuts 168, 168. The boxes 165 and 166 with their respective rolls are 25 adjusted toward and away from each other by means of a right and left adjusting screw 169 which is journaled to rotate in the frame of the machine and is rotated by means of a hand-wheel 170. It will thus be 30 seen that by means of the surface rolls 156 and 157 and the edge rolls 161 and 162, the surface and edges of the belt may be rolled after having been woven, so that the resultant fabric is smooth and even. These 35 rolls become necessary in fabric of the character hereinbefore set forth—that is, in belts formed of covered wire strands, said strands being somewhat inflexible as compared with cords or thread and, therefore, 40 not being easily formed into a fabric having a smooth surface without the aid of the forming rolls hereinbefore described.

The lay and reed and mechanism by which they are operated by means of which 45 the filling strands are beaten up are illustrated in Figs. 1, 2, 3, 5, 15, 16 and 17. Referring to these figures and more particularly to Figs. 5, 15, 16 and 17, it will be seen that the reed 171 consists of a plurality 50 of fingers 172 adjustably fastened to a shaft 173 by means of clamp nuts 174. The shaft 173 is rigidly fastened to links 175, 175 which are pivoted at their lower ends to auxiliary rocker arms 176 and 177 which are 55 rigidly fastened to the cross-shaft 178, said cross-shaft being journaled at its opposite ends in the primary rocker arms 179 which constitute the lay. The primary rocker arms 179 constituting the lay are journaled 60 to rock upon studs 180, 180 which are fastened to brackets 181 which, in turn, are fast to the frame of the machine. A spring 182 is fastened at one end thereof to the primary rocker arm 179 and at the other end 65 to the frame of the machine. The oppo-

site ends of the shaft 173 are adapted to slide in slots 183 provided in the rocker arms 179. Each of the rocker arms 176 and 177 has a stop-screw 184 thereon which are adapted to abut against the studs 180 when 70 the rocker arms are in the position illustrated in Figs. 16 and 17.

A rocking motion is imparted to the shaft 178 by means of an arm 185 fast thereto and connected by a link 186 to a cam lever 75 187 which is pivoted upon the shaft 148, and has a cam roll 188 journaled thereon and adapted to bear against a cam 189 fast to the sleeve 81.

The operation of the lay and reed in beating up the filling is as follows: The cam 189 rocks the cam lever 187 and through the link 186 communicates a rocking movement to the arm 185, the rock-shaft 178 and auxiliary rocker arms 176 and 177. These 85 rocker arms, in turn, move the links 175 upwardly, together with the shaft 173 which is fastened thereto and which slides longitudinally of the slots 183 in the primary rocker arms 179. The fingers 172 are thus 90 moved longitudinally of the rocker arm 179 from the position illustrated in Fig. 15 to that illustrated in Fig. 16. Thus the fingers are inserted between the warp strands. A continuation of the rocking motion herein 95 before referred to of the auxiliary rocker arms 176 and 177 causes the stop screws 184 to abut against the studs 180 and at this time a continued rocking movement of the rocker arms will cause the auxiliary rocker 100 arms 176 and 177 to rock and also the primary rocker arms 179 as one piece. The auxiliary rocker arms 176 and 177 and the primary rocker arms 179 thus constitute, as a whole, a lay pivoted upon the studs 180, 105 and this rocking movement will move the fingers constituting the reed from the position illustrated in Fig. 16 to that illustrated in Fig. 17, thus beating up the filling 72. The link 186 is adjustably attached to the 110 arm 185 by means of the stud 190 which projects into a slot 191 in said arm and is clamped to said arm by a nut 192.

We will now proceed to describe the reversible and auxiliary clutch mechanisms 115 and the instrumentalities by which they are operated.

Referring to Figs. 1, 2, 3, 8, 10, 11, 12, 18, 19 and 20, the reversible clutch sleeve 193 is keyed to the shaft 37 and has teeth at its 120 opposite ends adapted to engage teeth upon the adjacent faces of the gears 34 and 36. Said clutch is moved longitudinally of the shaft 37 by a clutch lever 194 pivoted at 195 to brackets 196. The clutch lever 194 125 has pivoted to its lower end, at 197, a rocker plate 198, and the upper end of said rocker plate is connected by a link 199 to a rocker arm 200. The link 199 is slotted at its left hand end and engages a pin 199' fast to a 130

rocker arm. Said rocker arm 200 is fast to a rock-shaft 201 adapted to rock in a suitable bearing formed in the frame of the machine, said rocker arm having fastened 5 to its rear end (Fig. 23) another rocker arm 202 which is connected by a link 203 to a rocker arm 204 fast to a rock-shaft 205 and having fastened to its forward end a rocker arm 206 which is adapted to be engaged 10 by an arm 207 fast to the slide 54. The link 199 has a cross-pin 208 fast thereto (Fig. 11) which projects into slots 209 formed in the clutch-lever 194 and concentric with the pivot 197 of the rocker-plate 15 198. The link 210 is pivotally connected to 202 by a cross-pin 212 which is fast to the rocker arm 202. Said link 210 is connected at the right hand end thereof (Fig. 18) with a rocker arm 213 pivoted at 214 to the 20 frame of the machine. Said rocker arm 213 is further connected by a link 215 to a rocker arm 216 connected by a link 217 to a rocker-arm 218 fast to a shaft 219 adapted to rock in bearings formed in the frame of 25 the machine, and having fastened thereto a rocker-arm 220 which is adapted to be engaged by the arm 221 fast to the carrier slide 54, when said carrier slide is at the extreme right of its movement, as viewed 30 from the front of the machine. A rod 222 is adapted to slide in the bracket 223 (Fig. 3) fast to the frame of the machine and is connected at the right hand end thereof to a pin 224 to the auxiliary clutch lever 225 35 which is pivoted at 226 to a bracket 227 fast to the frame of the machine. Collars 228 and 229 are fastened to the rod 222. Collars 230 and 231 are slidable upon said rod and springs 232, 232 encircle the rod 40 222 and are interposed between the collars 228 and 230 and the collars 229 and 231. The distance to which the collars 230 and 231 can slide upon the rod 220 toward each other is limited by suitable cross-pins 230' 45 and 231' extending through said rod.

The auxiliary clutch slide 76 is normally held with its teeth in engagement with the teeth upon the side of the gear 34 by spiral springs 233, 233, but is forced away from or 50 toward the right (Fig. 19) by an inclined projection 234 thereon which is adapted to engage a corresponding incline upon a lever 235 (Figs. 10 and 19) pivoted at 236 to the bracket 227 and having a friction roll 237 thereon which is adapted to bear against the upper cam-shaped surface 238 of the rocker-arm 213. A spring 239 holds the friction roll 237 in contact with the cam surface 238 of the rocker arm 213. The upper end of the lever 225 is provided with a roll 240 which projects into a cam groove 241 in the cam 242. The cam 242 is fastened to the sleeve 81 and has a latch 243 located in said cam groove and pivoted to said cam 55 at 244.

In the form of our invention hereinbefore described, as will be seen by reference to Figs. 21 and 22, Fig. 22 being an enlarged plan view of the upper guide-rolls 113, 114 and 115, each heddle has an independent set 70 of connections 105 and 106 attached to the reciprocating frame 111 and the guide pulleys 113, 114, 115, 107 and 116 are all in the same vertical plane, but in order to simplify the construction, as illustrated in 75 Figs. 24 and 25, two heddles 101, 101 may have a single set of connections 105', 106' and 106''. The reciprocating frame and the manner in which it is driven is the same in this case as in that illustrated in Fig. 13, but the guide pulleys 113, 114 and 115, instead of being in the same plane, are placed in different planes, the pulley 113 being in the same plane as the guide pulley 107 and the guide pulley 115 being in the same plane as the guide pulley 116, while the guide pulley 114 is placed midway between the guide pulleys 113 and 115. Thus, while the two heddles are in different planes, as required to guide two warps, one set of connections can be utilized, thus simplifying the construction and rendering it easier and 80 cheaper to manufacture.

The general operation of our improved loom is as follows: The warp strands are led into the machine from reels (not shown in the drawings) as will be seen by reference to Fig. 2, between the guide rolls 83 and 86, thence upwardly around the whip roll 91, thence through the heddles 101, 101 and from the heddles, to the woven fabric or belt. Said woven fabric or belt passes between the forming rolls 156 and 157 and between the edge forming rolls 161 and 162. Said belt then passes between the feed rolls 133 and 134 and from the feed rolls passes to a reel upon which it is wound, said reel not being shown in the drawings. Assuming the parts to be in the positions shown in Figs. 1, 2 and 18, with the lower reel and its slides at the left of the warp and with the upper reel and its slides at the right of the warp, the teeth of the reversible clutch sleeve 193 are in engagement with the teeth upon the gear 34. Said gear rotates in the direction of 95 the arrow thereon (Fig. 18) and the shaft 37 rotating in the same direction rotates the shafts 40 and 47 and hollow shafts or sleeves 42 and 50 in opposite directions, respectively, thus rotating the gears 43 and 44 and the gears 51 and 52 in the proper directions to move the upper reel 64, with its slides, toward the left, and the lower reel 61, with its slides, toward the right (Fig. 1). When the carrier slides 54 and 63 first start to move across the shed, the auxiliary reel slides 59 and 66 will move with their respective carrier slides until the tension upon the respective filling strands upon said reels tightens 100 sufficiently to hold said reels while the car- 105

rier slides 54 and 63 continue their movement across the shed. The reels will remain in a stationary position until the stop 62 at the left hand end of the carrier slide 54 and the corresponding stop at the right of the upper carrier slide 63 abut against their respective auxiliary or reel slides 59 and 66, whereupon a continued movement of the carrier slides will cause the reels and their auxiliary slides upon which they are journaled to move across the shed until the carrier slide 54 and its reel pass outside the shed to the right thereof and the carrier slide 63 with the upper reel 64 and its auxiliary slide 66 pass out at the left of the shed, and thus two picks of the filling will be simultaneously laid across the shed between the warp strands, the same being guided by the guide rolls 73, 73 upon the 20 guide frames 75.

When near the end of its movement toward the right, the arm 221 upon the carrier slide 54 will engage the rocker arm 220, tipping said rocker arm and its rocker shaft 219, together with the rocker arm 218, from the position shown in Fig. 18 to that shown in Fig. 19, thus moving the link 217 upwardly, rocking the rocker arm 216 to the position shown in Fig. 19 and moving the link 215 toward the right (Fig. 19) thus tipping the rocker arm 213, to which the link 215 is connected, from the position shown in Fig. 18 to that shown in Fig. 19, and at the same time moving the link 210 toward the right and rocking the rocker arm 200 from the position shown in Fig. 18 to that shown in Fig. 19, which tipping of the rocker arm 200 causes the rocker arm 202 to be tipped toward the right and moving the link 199, which is connected to said rocker arm 202 at its left hand end, toward the right until the cross-pin 208 moves to the right hand end of the slots 209 in the clutch lever 194. At the same time the link 203, which is attached to the horizontal arm of the rocker arm 202, is moved downwardly, thus tipping the rocker arms 204 and 206 from the position illustrated in Fig. 18 to that shown in Fig. 19. As the link 199 is thus moved toward the right from the position shown in Fig. 18 to that shown in Fig. 19, the rocker plate 198 is first tipped from the position shown in Fig. 18 to that shown in Fig. 19, relatively to the lever 194 and the last part 55 of the movement of the link 199 toward the right will rock the clutch lever 194 upon its pivot and move the clutch slide 193 into the central position and out of engagement with the teeth upon the gear 34. Thus the rotation of the shaft 37 will be stopped and the reels and their slides will become stationary. As the rocker arm 213 is moved from the position illustrated in Fig. 18 to that shown in Fig. 19, as hereinbefore described, the 60 cam-shaped surface of the upper end thereof

will move the roll 237 and the lever 235 to which it is attached (Fig. 10) so as to rock the lever 235 upon its pivot 236, thus moving the upper end of the lever 235 outwardly from the center of the shaft 37 and releasing the auxiliary clutch slide 76, whereupon said clutch slide is moved toward the left (Fig. 3) by the spiral springs 223 into the position illustrated in Fig. 19, with its teeth in engagement with the teeth on the gear 34. As soon as this happens the clutch 76 will be rotated, thus, through the lugs 80 which project into the grooves or notches 79 in said clutch slide, rotating the sleeve 81 from the end of which the lugs 80 project. As soon as the sleeve 81 begins to rotate the cam 242 thereon will be rotated and thus the lever 225 will be rocked by said cam from the position illustrated in Fig. 18 to that illustrated in Fig. 19. This rocking of the lever 225 will move the rod 222 toward the right into the position shown in Fig. 19.

The clutch sleeve 81 is now given one rotation, thus operating the different mechanisms hereinbefore described for reciprocating the heddles, for operating the take-up, for feeding the belt, and for operating the beating-up mechanism. When the cam 242 first begins its rotation hereinbefore described, the roll upon the lever 225 will pass out of engagement with the latch 243 and in passing said latch will tip it from the position illustrated in full lines (Fig. 12) to that shown in dotted lines in said figure, or from the position shown in full lines (Fig. 18) to that shown in full lines (Fig. 20). Then, when said cam has nearly completed its rotation the roll upon the lever 225 will engage the latch 243 and pass to the left of said latch, as shown in Fig. 20, thus tipping the lever 225 from the position illustrated in Fig. 19 to that shown in Fig. 20, moving the lower end of said lever toward the right (Fig. 19) and by means of the rod 222 rocking the clutch lever 194 from the position shown in Fig. 19 to that shown in Fig. 20 and moving the clutch slide 193 toward the left into engagement with the gear 36.

It will be understood that as the sleeve 81 comes to the end of its rotation, the inclined piece 234 upon the auxiliary clutch slide will engage the similar incline upon the lever 235 and move said auxiliary clutch slide toward the right, with its teeth out of engagement with the teeth upon the gear 34, as shown in Fig. 20. Thus, the sleeve 81, with the parts connected therewith and the different mechanisms for operating the take-up, feed, heddles, and beating-up mechanism, will come to a state of rest. Now, the slide 193 being in engagement with the gear 36 and as said gear rotates in the direction of the arrow thereon (Fig. 20) but in the opposite direction to that in which

the gear 34 is rotated, it will be seen that through the shaft 37 and vertical shafts 40 and 47, vertical hollow shafts 42 and 50, the gears which mesh into the racks upon 5 the carrier slides will reverse the motion of said slides and their reels hereinbefore described and will move them through the shed back into the position shown in Fig. 1, laying two filling threads again between 10 the warp strands in the shed. When the carrier slides arrive at the end of their movement toward the left and right, respectively, the lower carrier slide will operate the rocker arms 206 and 204 to raise the link 203 and move the connecting parts into 15 the position illustrated in Figs. 1 and 18. The auxiliary clutch slide will be thrown into engagement and the operation of the parts hereinbefore described will be repeated. Thus, an alternate intermittent motion 20 will be imparted to the slides and their reels from one side of the shed to the other and while the reels and their slides are stationary the sleeve and its connecting mechanism, 25 through the auxiliary clutch, will operate the take-up, feed, heddles, and beating up mechanism. These different movements 30 will take place alternately and intermittently, first operating through the reversible clutch mechanism, then throwing said reversible clutch mechanism out of operation and operating through the auxiliary clutch mechanism so long as the pulley upon the main driving shaft 30 is rotated.

35 Having thus described our invention, what we claim and desire by Letters Patent to secure is:

1. In a loom, a reel for the filling, a slide upon which said reel is journaled, a carrier slide on which said reel slide is adapted 40 to reciprocate, and means to impart a reciprocatory movement to said slides transversely of and between the warp strands.

2. In a loom, a carrier for the filling, instrumentalities adapted to impart a reciprocatory movement to said carrier transversely of and between the warp strands, and a guide supported upon and extending laterally from said carrier and longitudinally of the warp strands adapted to guide 50 said filling between the warp strands of the shed.

3. In a loom, a carrier for the filling, instrumentalities adapted to impart a reciprocatory movement to said carrier transversely of and between the warp strands, a guide frame secured to said carrier, and a pair of guide rolls journaled on said frame and adapted to guide said filling between the 60 warp strands of the shed.

4. In a loom, a reel for the filling, a slide upon which said reel is journaled, a carrier slide on which said reel slide is adapted to reciprocate, a rack on said carrier slide, 65 ways on opposite sides, respectively, of the

shed in which said carrier slide is adapted to move, and gears on opposite sides, respectively, of said shed adapted to engage said rack, whereby said reel and the slides are adapted to be moved through said shed. 70

5. In a loom, a reel for the filling, a slide upon which said reel is journaled, a carrier slide upon which said reel slide is adapted to reciprocate, stops on said carrier slide at opposite ends thereof, respectively, adapted to limit the distance to which said reel slide may move on said carrier slide, and means to impart a reciprocatory movement to said carrier slide transversely of and between the warp strands. 75

6. In a loom, a reel for the filling, a slide upon which said reel is journaled, a carrier slide on which said reel slide is adapted to reciprocate, a rack on said carrier slide, stops on said carrier slide at opposite ends thereof, respectively, adapted to limit the distance to which said reel slide may be moved on said carrier slide, and gears on opposite sides, respectively, of said shed adapted to engage said rack, whereby said reel and its slides are adapted to be reciprocated through said shed. 80

7. In a loom, a reel for the filling, a slide upon which said reel is rotatably mounted, a rack on said slide, ways on opposite sides, respectively, of the shed in which said slide is adapted to move, gears on opposite sides, respectively, of said shed adapted to engage said rack, and mechanism to reverse the direction of rotation of said gears, whereby a reciprocatory motion is imparted to said slide and reel, one of said gears being arranged to mesh with said rack before said rack passes out of mesh with the other of said gears. 95

8. In a loom, a reel for the filling, a slide upon which said reel is rotatably mounted, a rack on said slide, ways on opposite sides, respectively, of the shed in which said slide is adapted to move, gears on opposite sides, respectively, of said shed adapted to engage said rack, and instrumentalities adapted to stop the rotation of said gears and subsequently reverse their direction of rotation, whereby an intermittent reciprocatory motion is imparted to said slide and reel, one of said gears being arranged to mesh with said rack before said rack passes out of mesh with the other of said gears. 100

9. In a loom, two slides, instrumentalities adapted to impart an intermittent reciprocatory movement to said slides simultaneously transversely of and between the warp strands in opposite directions, respectively, and a reel for the filling rotatably mounted 110 on each of said slides, respectively. 120

10. In a loom, two carrier slides, two reel slides adapted to be reciprocated on said carrier slides, two reels journaled on said reel slides, and instrumentalities adapted to im- 130

- part an intermittent reciprocatory movement to said carrier slides transversely of and between the warp strands in opposite directions, respectively.
5. 11. In a loom, two carrier slides, two reel slides adapted to be reciprocated on said carrier slides, two reels journaled on said reel slides, stops on said carrier slides at opposite ends thereof, respectively, adapted to limit the distance to which said reel slides may be moved on their respective carrier slides, and instrumentalities adapted to impart an intermittent reciprocatory movement to said carrier slides transversely of and between the warp strands in opposite directions, respectively.
10. 12. In a loom, two carrier slides, a reel for the filling rotatably mounted on each of said slides, respectively, a rack on each of said slides, respectively, a pair of gears on opposite sides, respectively, of the shed adapted to engage said racks, mechanism adapted to rotate the gears of each pair, respectively, simultaneously in opposite directions, whereby said carrier slides and their respective reels may be moved simultaneously in opposite directions across the shed.
15. 13. In a loom, two carrier slides, a reel for the filling rotatably mounted on each of said slides, respectively, a rack on each of said slides, respectively, a pair of gears on opposite sides, respectively, of the shed adapted to engage said racks, mechanism adapted to rotate the gears of each pair, respectively, simultaneously in opposite directions, whereby said carrier slides and their respective reels may be moved simultaneously in opposite directions across the shed, and instrumentalities adapted to reverse the direction of rotation of said gears, whereby a reciprocatory motion is imparted to said slides and reels.
20. 14. In a loom, two carrier slides, a reel for the filling rotatably mounted on each of said slides, respectively, a rack on each of said slides, respectively, a pair of gears on opposite sides, respectively, of the shed adapted to engage said racks, mechanism adapted to rotate the gears of each pair, respectively, simultaneously in opposite directions, whereby said carrier slides and their respective reels may be moved simultaneously in opposite directions across the shed, and instrumentalities adapted to stop the rotation of said gears at opposite ends of the movement of said slides and subsequently to reverse the direction of rotation of said gears, whereby a reciprocatory motion is imparted to said slides and reels.
25. 15. In a loom, two carrier slides, a reel for the filling rotatably mounted on each of said slides, respectively, a rack on each of said slides, respectively, a pair of gears on opposite sides, respectively, of the shed adapted to engage said racks, mechanism
- adapted to rotate the gears of each pair, respectively, simultaneously in opposite directions, whereby said carrier slides and their respective reels may be moved simultaneously in opposite directions across the shed, a clutch reversing mechanism, instrumentalities operated by one of said slides at opposite ends of its movement to throw said clutch out of operation and subsequently into operation to stop and reverse said gears, whereby an intermittent reciprocatory motion is imparted to said slides and reels.
30. 16. In a loom, two filling carriers one located above the other, instrumentalities adapted to impart an intermittent reciprocatory motion to said carriers transversely of and between the warp strands in opposite directions, respectively, and a guide on each of said carriers, respectively, adapted to lead the filling between the warp strands adjacent to the fell of the fabric.
35. 17. In a loom, a heddle adapted to guide a warp, flexible connections attached to opposite ends of said heddle, guide pulleys over which said connections extend, a reciprocatory frame adapted to be moved in a plane extending transversely of said heddle to which said connections are fastened, whereby a reciprocatory motion may be imparted to said heddle, and means supported on said frame to adjust the tension on said connections.
40. 18. In a loom, a heddle adapted to guide a warp, flexible connections attached to opposite ends of said heddle, guide pulleys over which said connections extend, a reciprocatory frame adapted to be moved in a plane extending transversely of said heddle to which said connections are fastened, a rack on said frame, a gear meshing into said rack, mechanism to rotate said gear in opposite directions, and a clutch adapted to throw said last named mechanism into and out of operation, whereby an intermittent reciprocatory motion may be imparted to said frame and heddle.
45. 19. In a loom, a pair of feed rolls for the fabric, mechanism to impart an intermittent rotary motion to said rolls, and a pair of rolls adapted to bear against opposite edges of said fabric.
50. 20. In a loom, a pair of feed rolls for the fabric, mechanism to impart an intermittent rotary motion to said rolls, a pair of rolls adapted to bear against opposite edges of said fabric, and means to adjust said rolls toward and away from each other.
55. 21. In a loom, a lay consisting of a primary rocker arm and an auxiliary rocker arm pivoted to said primary rocker arm, a reed adapted to slide on said primary rocker arm and connected to said auxiliary rocker arm, and mechanism to impart a rocking motion to said auxiliary rocker arm, said auxiliary rocker arm adapted to engage said

primary rocker arm when rocked thereon, whereby said reed may be reciprocated on said primary rocker arm and said primary and auxiliary rocker arms may be rocked about a common pivot.

22. In a loom, a slide, a reel for the filling rotatably supported on said slide, a clutch reversing mechanism adapted to impart an intermittent reciprocatory motion to said slide transversely of the warp, a plurality of heddles, an auxiliary clutch mechanism adapted to impart an intermittent reciprocatory motion to said heddles to change the shed, and instrumentalities operated by said slide at opposite ends of its movement to operate said clutch mechanisms for the purpose specified.
- 10 23. In a loom, a slide, a reel for the filling

rotatably supported on said slide, a plurality of heddles, a lay, a feed for the warp, a take-up mechanism, a clutch reversing mechanism adapted to impart a reciprocatory motion to said slide transversely of the warp, and an auxiliary clutch mechanism adapted to operate said heddles, lay, feed, and take-up, while said slide is stationary. 20 25

In testimony whereof we have hereunto set our hands in presence of two subscribing witnesses.
